(57) **CLAIM**

The ornamental design for bat cane, as shown and described.

DESCRIPTION

FIG. 1 is a top front elevation view of the bat cane of the instant invention.

FIG. 2 is a top rear elevation view thereof.

FIG. 3 is a right side view thereof

FIG. 4 is a left side view thereof.

FIG. 5 is a top view thereof; and,

FIG. 6 is a bottom view thereof.

The broken lines in the drawings depict portions of the bat cane that form no part of the claimed design.
